(57) **CLAIM**

The ornamental design for an exhaust pipe, as shown and described.

DESCRIPTION

1. Exhaust pipe
- 1.1 : Right
- 1.2 : Left
- 1.3 : Top
- 1.4 : Bottom
- 1.5 : Front
- 1.6 : Back
- 1.7 : Perspective
- 1.8 : Perspective
- 1.9 : Perspective
- 1.10 : Perspective
